MEANS FOR IMPROVING THE SENSITIVITY AND THE RESPONSE CHARACTERISTICS OF VELOCITY MICROPHONES

Harry F. Olson, Princeton, and John Preston,
Metedeconk, N. J., assignors to Radio Corpora-
tion of America, a corporation of Delaware

Application June 30, 1948, Serial No. 36,196

12 Claims. (Cl. 179—115.5)

1

This invention relates to electro-acoustical translating apparatus, and more particularly to a microphone of the dynamic type.

Sensitivity and wide frequency range have always been two incompatible factors in electro-acoustical translating apparatus, such as microphones, especially the type of apparatus used in radio broadcasting. With an extension of the frequency band of radio broadcasting, as in the case of frequency modulation and high quality amplitude modulation, noise in the system becomes a very important problem.

The velocity type microphone, to which our present invention is directed, is almost universally employed in broadcast practice, since the sensitivity is as great as, or greater than other types of microphones in use at the present time. Since the velocity type microphone is highly sensitive, the signal to noise ratio is superior to that of other microphones. However, the noise problem in broadcasting still exists even with the use of velocity microphones. One solution of the problem is to make the microphone more sensitive. While weight is not a factor, if it is kept within reason, restrictions on size must be considered. We have provided an improved velocity microphone, which not only overcomes many of the problems encountered by similar microphones in use at the present time, but which also has greater sensitivity and improved response characteristics. Thus, the primary object of our present invention is to provide an improved velocity type microphone the sensitivity and the response characteristics of which are greatly improved over those of similar, prior art microphones, with no substantial increase in the size thereof.

It is also an object of our invention to provide an improved velocity type microphone which will eliminate or reduce non-uniform response with respect to frequency.

It is another object of our invention to provide an improved velocity type microphone which will average out diffraction and resonance effects and provide a smoother response frequency characteristic.

It is a further object of our invention to provide a high sensitivity velocity microphone in which the difference in sound wave pressure on the front and back of the ribbon diaphragm will continue to increase linearly with the frequency and thereby prevent the falling off of response in the high frequency range.

It is also an object of our invention to provide a high sensitivity velocity type microphone which is simple in construction and at the same time highly efficient in use.

In accordance with our present invention, we have provided an improved velocity type microphone in which we make use of a pair of pole pieces each of which has an intermediate portion of reduced cross section to shorten or reduce the acoustic path from the front to the back of

the ribbon diaphragm. An unsymmetrical magnetic field structure is connected to the ends of the pole pieces in order to average out diffraction and resonance effects characteristic of symmetrical field structures. In addition thereto, the microphone is also equipped with a high frequency equalizer of the kind disclosed in our co-pending application Ser. No. 29,844, filed May 28, 1948, for maintaining suitable response throughout the high frequency range.

The novel features of our invention, both as to its organization and method of operation, will best be understood from the following detailed description when read in connection with the accompanying drawing, in which

Fig. 1 is a front elevation, partly cut away of a velocity type microphone constructed in accordance with our present invention.

Fig. 2 is a front elevation of the microphone field structure shown in Fig. 1, with the high frequency equalizer plates removed.

Fig. 3 is a side view, in section, of the field structure illustrated in Fig. 2, equipped with high frequency equalizer plates, and taken on the line 3—3 of Fig. 2.

Fig. 4 is a cross section of the pole pieces and ribbon diaphragm of our improved microphone, taken on the line 4—4 of Fig. 2.

Fig. 5 is a front elevation of a modification of a velocity microphone field structure constructed in accordance with our invention, with the high frequency equalizer plates removed, and

Fig. 6 is a side view, in section, of the field structure illustrated in Fig. 5 equipped with high frequency equalizer plates, and taken on the line 6—6 of Fig. 5.

Referring, now, in detail to the drawing in which the same reference numerals refer to like elements, there is shown in Fig. 1, a velocity type microphone 1 constructed in accordance with our invention. The microphone 1 is pivotally mounted on a support 3 of conventional design, and comprises, essentially, a ribbon diaphragm 5, a pair of pole pieces 7, 9 and a pair of magnets consisting of top and bottom units 11, 13.

According to one form of our invention, as shown in Figs. 1, 2, 3 and 4, the microphone 1 is provided with a pair of elongated pole pieces 7, 9 disposed in spaced, parallel relation to provide an air gap 15 between adjacent flat faces 17, 19 of the pole pieces. The pole pieces may be of any desired shape. As shown in Fig. 4, the pole pieces illustrated are substantially circular in cross section with the exception that they are provided with the flat faces 17, 19 disposed on adjacent sides of the pole pieces 7, 9. Each of the pole pieces 7, 9 has an intermediate portion, the cross sectional area of which decreases toward the center thereof, forming longitudinal concave surfaces 25, 27 around the pole pieces except on their adjacent sides, or flat faces 17, 19. The cut-out intermediate portion of the pole pieces 7, 9 serves to reduce the acoustic path from the

front to the back of the ribbon, whereby good response is maintained throughout the high frequency range.

The ribbon diaphragm 5 is suspended in the air gap 15 between the pole pieces 7, 9, and is held in place by two insulated clamps 29, 31 carried by the field structure. The ribbon 5 is also maintained in spaced relation to the pole pieces so that it will be free to vibrate in response to differences in sound wave pressures on the front and back of the ribbon.

The top and bottom units 11, 13 comprise two substantially U-shaped magnetic structures which are attached to opposite ends 33, 35, 37, 39 of the pole pieces 7, 9 for supplying magnetic flux across the air gap 15 in a manner well known in the art. Referring to Fig. 3 of the drawing, it will be seen that the bottom unit 13 is larger than the top unit 11, thus forming an unsymmetrical field structure for the microphone. For simplicity of construction and to facilitate manufacture, the units 11, 13 contain combinations of magnetizing bodies or permanent bar magnets each of equal size made from material having a high degree of retentivity, such as Alnico V (composed of aluminum 8 percent, nickel 14 percent, cobalt 24 percent, copper 3 percent, and the remainder iron). As shown in Figs. 2 and 3 of the drawing, the top unit 11 has two bar magnets 41, 43 disposed in spaced, parallel relation, with the ends 45, 47 of these bar magnets connected by a soft iron plate element 49. The opposite ends 51, 53 of the bar magnets are respectively connected to outer pole members 55, 57 which, in turn, are connected to the top ends 33, 37 of the pole pieces 7, 9. The bottom unit 13 has two pairs of bar magnets 63, 65, each of which is the same as the bar magnets 41, 43 in the top unit 11. The bar magnets of each pair are joined or held together by means of welding 66, or other suitable means. As in the case of the top unit, the ends 67, 69 of each pair of bar magnets 63, 65 are connected by a soft iron plate element 71 and the opposite ends 73, 75 thereof are connected, respectively, to outer pole members 77, 79 which, in turn, are connected to the lower ends 35, 39 of the pole pieces 7, 9. The plate elements and the outer pole members should preferably be made from an alloy or combination of alloys which is capable of carrying a high flux density before becoming saturated. (For example, we have found that an alloy containing 50 percent cobalt, and 50 percent iron will carry more flux than pure iron is satisfactory for the field structure of our present invention.)

As pointed out above, the use of two bar magnets 41, 43 in the top unit 11 and two pairs of bar magnets 63, 65 in the bottom unit 13 defines an unsymmetrical field structure. By providing an unsymmetrical field structure, two advantages result. (1) The field structure forms two cavities 78, 80 of different dimensions between the bar magnets the plate elements and the ends of the pole pieces. Under these conditions a fundamental resonance at different frequencies is obtained which averages out the deleterious effects of these resonances upon the response. (2) Providing an unsymmetrical field structure also varies the path length between opposite sides of the ribbon diaphragm, as a result of which, the necessary difference in pressure, due to the difference in phase, is also varied. These different path lengths extend any definite cut-off frequency in the response, which, under symmetrical conditions would occur.

Our improved velocity microphone 1 is also

provided with a high frequency acoustic equalizer of the type described in our above-identified co-pending application. The equalizer comprises two perforated plates or screens 81, 83 which are disposed in spaced, parallel, overlapping relation to the ribbon diaphragm 5. The equalizer plates 81, 83, may be supported in any suitable manner to insulate them from the magnetic structure (for example, by attaching them to the insulated ribbon clamps 29, 31). Each of the plates has a plurality of perforations 85. The size of the perforations or openings 85, as well as the spacing between the plates 81, 83 and the ribbon 5 are determined according to the frequency range to be compensated for, and may be varied according to the condition to be corrected. The plates 81, 83 form resonance chambers on opposite sides of the ribbon 5 and operate as reflectors for sound waves transmitted through the perforations whereby a standing wave system is produced between the plates which will maintain the necessary difference in sound wave pressure on the front and back of the ribbon and prevent the falling off of response in the high frequency range.

Referring to Figs. 5 and 6, there is shown a modified form of field structure 91 for a velocity type microphone constructed in accordance with our invention. The microphone itself comprises the same essential elements as that shown in Figs. 1 through 3 and differs primarily in respect to the field structure. The modified field structure 91 comprises, essentially, a pair of pole pieces 95, 97, and top and bottom magnet units 99, 101. The pole pieces are spaced apart to provide an air gap 102 in which a diaphragm 93 is received. The top magnet unit 99 comprises two cylindrical bar magnets 103, 105 which are disposed in spaced, parallel relation so as to provide an air space 107 between them. The bar magnets 103, 105 have two outer pole elements or members 109, 111 respectively connecting the ends of the magnets to the upper ends 113, 115 of the pole pieces 95, 97 to provide a substantially U-shaped magnetic structure. The bottom magnet unit 101 is similar to the top unit 99 except that it has three bar magnets 117, 119, 121 instead of two as in the top unit. Thus, a modified unsymmetrical form of field structure is provided in which the top and bottom units have unequal magnetic flux densities. The bottom unit 101 is also provided with outer pole elements or members 123, 125 which connect the ends 127, 129 of the bar magnets 117, 119, 121 to the lower ends 131, 133 of the pole pieces 95, 97. As in the case of the top unit 99, the bar magnets 117, 119, 121 are disposed in spaced, parallel relation so as to provide air spaces 135, 137 between them. The air spaces 107, 135, 137 between the bar magnets in the top and bottom units serve to reduce resonance in the spaces 136, 138 between the bar magnets and the ends of the ribbon and pole pieces.

Also, in our modified form of field structure we have provided pole pieces 95, 97 with intermediate sections having concave surfaces 139, 141, the same as the concave surfaces 25, 27 shown in Figs. 1 through 3, for reducing the sound wave path from the front to the back of ribbon diaphragm 93. The modified form of field structure is also provided with high frequency acoustic equalizer plates 145, 147 each having a plurality of openings 149, the same as in the modification shown in Figs. 1 through 3.

While the field structure shown in Figs. 1 through 3 shows the axis of the bar magnets to

be parallel to the axis of the pole pieces, and the modified field structure 91 shown in Figs. 5 and 6 shows the axis of the bar magnets to be perpendicular to the axis of the pole pieces, this is merely illustrative. Position of the bar magnets with respect to the pole pieces, their size, and number are not controlling. For the purposes of our invention, it is necessary, however, that an unsymmetrical magnetic field structure be provided in order to average out diffraction and resonance effects inherent in symmetrical structures. While we have illustrated but two forms of unsymmetrical field structure herein, it is obvious that other combinations and arrangements of bar magnets may be utilized to advantage.

It will readily be seen by those persons skilled in the art, that we have provided a new type of magnetic and acoustic field structure for the velocity type microphone which distinctly improves the sensitivity and response thereof. While we have described but two modifications of our invention, it will be recognized that various other changes and modifications will, no doubt, readily suggest themselves. We, therefore, desire that the particular form of our invention described herein be considered as illustrative and not as limiting.

What is claimed is:

1. A magnetic structure for sound translating apparatus comprising a pair of elongated pole pieces disposed in spaced relation to provide an air gap therebetween, each of said pole pieces having a flat face disposed longitudinally thereof on the side adjacent said air gap, and also having an intermediate portion of reduced cross section area forming longitudinal concave surfaces on all sides of said pole piece except on the side containing said flat face, and a magnetic field structure coupling the ends of said pole pieces to provide a continuous magnetic flux path between the pole pieces external to said air gap, the portion of said magnetic field structure which couples adjacent ends of said pole pieces at one end thereof being larger than the portion of said magnetic field structure which couples the opposite adjacent ends of said pole pieces.

2. A magnetic structure according to claim 1 characterized in that said magnetic field structure comprises a pair of magnets each having at least one magnetizing body, and pole members coupling said pole piece ends to said magnetizing bodies.

3. A magnetic structure according to claim 2 characterized in that each of said pair of magnets has at least one bar magnet of permanent magnet material, and further characterized in that one of said pair of magnets is composed of more bar magnets than the other of said pair.

4. A magnetic structure according to claim 1 characterized in that said magnetic field structure includes a pair of magnets, each of said magnets having a plurality of spaced bar magnets of permanent magnet material.

5. A magnetic structure according to claim 1 characterized in that said magnetic field structure comprises a pair of magnets having a plurality of permanent bar magnets disposed in spaced, parallel relation, each of said bar magnets having its axis disposed parallel to the axis of said pole pieces, characterized further by the addition of pole members connecting an end of said bar magnets to said pole pieces, and characterized also by the addition of a plate element

connecting the opposite ends of said bar magnets of each of said pair of magnets.

6. A magnetic structure according to claim 1 characterized in that said magnetic field structure comprises a pair of magnets, each one of said pair of magnets having at least one permanent bar magnet the axis of which is disposed perpendicular to the axis of said pole pieces, and characterized further by the addition of pole members connecting the ends of each of said bar magnets to said ends of said pole pieces.

7. In sound translating apparatus, the combination consisting of (1) a pair of elongated pole pieces disposed in spaced, parallel relation to provide an air gap therebetween, each of said pole pieces having a flat face disposed longitudinally thereof on the side adjacent said air gap, and also having an intermediate portion of reduced cross section area forming longitudinal concave surfaces on all sides of said pole piece except on the side containing said flat face, (2) a magnetic field structure comprising a pair of magnetizing bodies coupling the ends of said pole pieces to provide a continuous magnetic flux path between said pole pieces external to said air gap, (3) a ribbon diaphragm mounted in said air gap for movement in response to differences in sound wave pressure on opposite sides thereof, said magnetic field structure coupling adjacent ends of said pole pieces at one end thereof being larger than said magnetic field structure coupling the opposite adjacent ends of said pole pieces, and (4) a pair of plates having a plurality of perforations therein, said plates being mounted in spaced, parallel, overlapping relation to said ribbon diaphragm and forming resonance chambers on opposite sides thereof to provide a standing wave system for sound waves transmitted through said perforations.

8. Sound translating apparatus according to claim 7, wherein each of said magnetizing bodies comprises at least one bar magnet of permanent magnet material.

9. Sound translating apparatus according to claim 8 wherein each of said magnetizing bodies includes a pair of pole members connecting opposite ends of said magnets to adjacent ends of said pole pieces.

10. Sound translating apparatus according to claim 7, wherein said magnetizing bodies are disposed with their axes parallel to the axis of said pole pieces.

11. Sound translating apparatus according to claim 7, wherein one of said magnetizing bodies comprises at least two bar magnets of permanent magnet material, said bar magnets being mounted in spaced, parallel relation.

12. Sound translating apparatus according to claim 9, wherein said magnetizing bodies are disposed with their axes perpendicular to the axis of said pole pieces.
